COATING AND SHAPING DISPENSER FOR
BUILDING TAPESMerritt E. Smith and Sidney D. Berg,
White Sulphur Springs, Mont.

Application January 18, 1952, Serial No. 267,030

4 Claims. (Cl. 118—32)

1

This invention relates to a device for dispensing building tape from a roll of the same, coating said tape during the dispensing thereof with a supply of cement, and shaping the tape for application to room corners or coves.

More particularly, the present invention has reference to an improved dispenser of the type stated, wherein there is included a removable shaper attachment which can be taken out of the device whenever desired, for substitution of a different removable member so formed as to permit the tape to be dispensed in a flat condition.

The present invention, in this connection, constitutes a continuation-in-part of our copending patent application, Serial No. 244,523, filed August 31, 1951. In that application there was shown a coating dispenser for building tapes so formed as to cause the tape to be dispensed flat. This arrangement, of course, would be entirely satisfactory during the performance of most joint sealing operations, but would require that the tape be manually folded along its longitudinal center line prior to application thereof to a room corner or cove.

The main object of the present invention, accordingly, is to provide a coating dispenser of the type illustrated and described in our copending application, but so formed as to permit the insertion of a shaping attachment effective to fold the tape longitudinally during the dispensing thereof, whenever the tape is to be used at one of the special room locations indicated.

A further important object is to provide a coating dispenser of the character stated which will permit substitution of the shaper attachment with a maximum amount of speed and ease.

Yet another important object is to provide a coating dispenser as described which will be of simple formation involving comparatively few parts, but which will nevertheless be rugged and capable of use over a long period of time.

Other objects will appear from the following description, the claims appended thereto, and from the annexed drawing, in which like reference characters designate like parts throughout the several views, and wherein:

Figure 1 is a top plan view of a coating dispenser formed in accordance with the present invention, a portion of a roll of tape mounted therein being broken away;

Figure 2 is a side elevational view;

Figure 3 is a front end elevational view;

Figure 4 is a transverse sectional view taken on line 4—4 of Figure 2; and

Figure 5 is a perspective view, a portion being broken away, of the removable shaping means.

2

Referring to the drawings in detail, the improved coating dispenser formed in accordance with the present invention includes a flat, rectangular base 10 having depending feet 12 at the several corners thereof. Fixedly mounted upon and extended longitudinally of the base are upstanding, parallel side walls 14. The side walls 14 are of raised formation at one end, and formed in the inner faces of the raised end portions of the side walls are vertical grooves 16 receiving the opposite ends of a shaft or pin 18 on which a roll 20 of building tape is mounted. The roll 20 is rotatable upon and is disposed between the respective side walls 14, said side walls being in close spaced relation to the opposite side surfaces of the roll.

A flared hopper 22 is mounted upon the other ends of the side walls 14, and is formed open at its opposite ends. The hopper is removable from the position thereof illustrated in the several figures of the drawings, and to this end the hopper is provided at its lower end with angular mounting brackets 24 secured to opposite sides of the hopper and having depending flanges 26 supported upon and overlying the respective side walls 14.

Each flange 26 is formed, intermediate its ends, with a slot 28 opening upon the lower edge of the flange. A wing nut 30 is threadable upon a bolt 32 extended through the slot of each flange, the heads of the respective bolts (see Figure 4) being received in recesses formed in the inner faces of the respective side walls 14, and the shanks of said bolts projecting through the respective slots 28.

It will be readily appreciated that this construction will permit the hopper 22 to be removed from the position thereof illustrated in the drawings whenever desired, for insertion or removal of the shaper attachment.

The shaper attachment has been generally designated 34, and is of box-like formation. Thus, the attachment constitutes a lower extension of the hopper 22, and to this end is formed with parallel, vertical side plates 34 so spaced apart as to cause them to fit snugly against the inner faces of the respective side walls 14 when the attachment is positioned as in Figure 4. The side walls 36 of the attachment, as readily seen from Figure 3, are rigid with front and rear walls 38 of the attachment, completing the box formation referred to above, and the front and rear walls are extended beyond the side walls 36 to form tongues 40 adapted to be received within complementary vertical grooves formed in the respective side walls 14 of the dispenser.

This construction is one which permits the attachment to be inserted between the side walls 14 whenever desired, and the construction also permits the attachment to be removed from this location whenever it is desired that the building tape be dispensed in a flat condition.

Rigidly secured to the respective side walls 36 and front and rear walls 38 is a bottom plate 42 having a pair of parallel grooves 44 formed in its upper surface, said grooves 44 being disposed in parallel relation and extending longitudinally of the base 10.

A shaping rib 48 is fixedly mounted upon the bottom plate 42, and has its opposite side edges aligned with the inner side edges of the respective grooves 44. The cross-sectional shape of the rib 48 is of importance, and as will be seen from Figure 4, said rib is formed cross-sectionally in the shape of an isosceles triangle with angularly disposed shaping faces converging upwardly and intersecting at the longitudinal center line of the shaping rib. The shaping faces, it should be noted, are disposed at right angles to one another, so as to shape the building tape exactly for the fitting thereof into a conventional room corner or cove.

Formed in the front and rear walls 38 of the attachment are angular slots, the upper edges of which are parallel to and are spaced closely above the shaping faces of the rib 48. The lower edges of the slots 46 are defined by the shaping faces of the rib, and thus, a length of building tape can be extended fully through the box-like attachment, said tape being passed through the respective slots 46 and being shaped within the attachment.

One end of the rib 48 terminates at the front wall of the attachment. The other end, however, projects beyond the rear wall into the space defined between the side walls 14. The projecting portion of the shaping rib is of tapered formation, and comes to a point in spaced relation to the rear wall of the attachment.

As will be seen from Figure 5, the projecting end portions of the rib 48 has a pair of shaping surfaces 50 that converge both upwardly and in a direction away from the rear wall 32. As a result, the projecting end portion of the rib is increased progressively both in height and width in the direction of said rear wall. The arrangement has been found to produce beneficial effects, in that a length of building tape 52, when unwrapped from the roll 20, will be acted upon first by the projecting end portion of the shaping rib, so as to be gradually bent to shape without danger of its being torn during the operation.

A flexible rule 54 of conventional formation is preferably mounted adjacent one of the side walls 14 upon the base 10, so as to permit a measurement to be made of the tape 52 during the dispensing thereof.

Also, it is preferred that a cutting blade 56 be affixed to the front end of the base 10, said blade being of triangular formation and being inclined upwardly (Figure 2). By reason of the particular formation of the cutting blade 56, the length of tape 52 can be pulled downwardly thereagainst after a suitable amount of the tape has been drawn through the shaper attachment, and cut to the length selected.

At 58 we have illustrated an idler roller journaled in and extending between the respective side walls 14, said roller being adapted to hold the tape against upward movement within the

device, and being particularly effective when the roll 20 becomes smaller.

It is of importance that the shaper attachment illustrated in Figure 5 can be removed from its operative position whenever desired, for substitution of another box-like member which would be formed identically thereto, with the exception of the shaping rib 48 and associated slots 46. The box-like member to be substituted, as will be appreciated, would be formed merely with a flat bottom plate, and with horizontal slots contiguous to the bottom plate and formed in the respective front and rear walls. A member so formed would permit the tape to be dispensed in a flat condition.

In use of the dispenser illustrated and described, a supply of cement, not shown, is deposited within the hopper 22, and will fill the box-like shaper attachment 34. Thereafter, the tape is fed through the attachment, and will be coated with said cement while being simultaneously shaped to the desired cross-sectional configuration.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. A dispenser for coating and shaping building tapes comprising a base; a pair of spaced, upstanding side walls mounted thereon; means for mounting a roll of building tape for rotation between the side walls at one end of the base; a hopper removably mounted upon the side walls at the other end of the base and adapted for holding a supply of cement with which said tape is to be coated, said side walls having oppositely arranged grooves formed therein below the hopper; a receptacle having tongues projecting from opposite sides thereof slidably received within the grooves for removably supporting the receptacle on the base, said receptacle being formed as a lower extension of the hopper and having angular slots in opposite walls thereof for passage of tape unwound from the roll; and a shaping rib in said receptacle formed to a triangular cross-section and adapted for shaping of the tape to a selected cross-sectional configuration during movement of the tape through the receptacle.
2. A dispenser for coating and shaping building tapes comprising a base; a pair of spaced, upstanding side walls mounted thereon; means for mounting a roll of building tape for rotation between the side walls at one end of the base; a hopper removably mounted upon the side walls at the other end of the base and adapted for holding a supply of cement with which said tape is to be coated, said side walls having oppositely arranged grooves formed therein below the hopper; a box-like receptacle having tongues projecting from opposite sides thereof slidably received within the grooves for removably supporting the receptacle upon the base, said receptacle being formed as a lower extension of the hopper

and having slots of inverted V-shape formed in opposite walls thereof for passage therethrough of tape unwound from the roll; and a shaping rib in said receptacle having upwardly converging faces aligned with the lower edges of the slots, said rib being adapted for shaping of the tape to a selected cross-sectional configuration during movement of the tape through the receptacle.

3. A dispenser for coating and shaping building tapes comprising a base; a pair of spaced, upstanding side walls mounted thereon; means for mounting a roll of building tape for rotation between the side walls at one end of the base; a hopper removably mounted upon the side walls at the other end of the base and adapted for holding a supply of cement with which said tape is to be coated, said side walls having oppositely arranged grooves formed therein below the hopper; a box-like receptacle having tongues projecting from opposite sides thereof slidably received within the grooves for removably supporting the receptacle upon the base, said receptacle being formed as a lower extension of the hopper and having slots of inverted V-shape formed in opposite walls thereof for passage therethrough of tape unwound from the roll; a shaping rib in said receptacle having upwardly converging faces aligned with the lower edges of the slots, said rib being adapted for shaping of the tape to a selected cross-sectional configuration during movement of the tape through the receptacle; and an axial projection on one end of the rib extending out of the receptacle toward the first-named end of the base, said projection having shaping surfaces converging both upwardly and in a direction away from the receptacle to reduce the projection progressively in height and width in said direction and thereby effect a gradual shaping of the tape to an angular cross-section preliminary to final shaping thereof by the rib.

4. A dispenser for coating and shaping building tapes comprising a base; a pair of spaced, upstanding side walls mounted thereon; means for mounting a roll of building tape for rotation between the side walls at one end of the base; a hopper removably mounted upon the side walls

5 at the other end of the base and adapted for holding a supply of cement with which said tape is to be coated, said side walls having oppositely arranged grooves formed therein below the hopper; a box-like receptacle having tongues projecting from opposite sides thereof slidably received within the grooves for removably supporting the receptacle upon the base, said receptacle being formed as a lower extension of the hopper and having slots of inverted V-shape formed in opposite walls thereof for passage therethrough of tape unwound from the roll; a shaping rib in said receptacle having upwardly converging faces aligned with the lower edges of the slots, said rib being adapted for shaping of the tape to a selected cross-sectional configuration during movement of the tape through the receptacle; an axial projection on one end of the rib extending out of the receptacle toward the 10 first-named end of the base, said projection having shaping surfaces converging both upwardly and in a direction away from the receptacle to reduce the projection progressively in height and width in said direction and thereby effect a gradual shaping of the tape to an angular cross-section preliminary to final shaping thereof by the rib; and a cutting blade mounted upon one end of the base and having a V-shaped cutting edge, said blade being adapted for severing the tape 15 20 25 30 after passage thereof through the receptacle.
